VLADIMIR BOBRITSKY, OF NEW YORK, N. Y., ASSIGNOR TO THE GRIESS PFLEGER TANNING COMPANY, OF CINCINNATI, OHIO, A CORPORATION OF OHIO

DESIGN FOR AN ARTIFICIAL ANIMAL

Application filed March 5, 1931. Serial No. 38,939. Term of patent 7 years.

To all whom it may concern:

Be it known that I, VLADIMIR BOBRITSKY, a citizen of the United States, residing at New York city, in the county of New York and State of New York, have invented a new, original, and ornamental Design for an Artificial Animal, of which the following is a specification, reference being had to the accompanying drawing, forming a part thereof.

In the accompanying drawing, Figures 1 and 2 are side and end views, respectively, showing my new design.

I claim:

The ornamental design for an artificial animal, as shown.

VLADIMIR BOBRITSKY.
